UNITED STATES PATENT OFFICE.

OWEN F. LEIBERT, OF BETHLEHEM, PENNSYLVANIA.

BREECH MECHANISM FOR ORDNANCE.

SPECIFICATION forming part of Letters Patent No. 516,788, dated March 20, 1894.

Application filed November 1, 1893. Serial No. 489,740. (No model.)

To all whom it may concern:

Be it known that I, OWEN F. LEIBERT, a citizen of the United States, residing at Bethlehem, in the county of Northampton and State 5 of Pennsylvania, have invented certain new and useful Improvements in Breech Mechanism for Guns, of which the following is a specification.

My invention relates to breech mechanisms for guns, and more particularly to that class of breech mechanism wherein the breech-block or plug is unlocked, withdrawn and swung to one side of the breech by a continuously operating mechanism, and whereby the 15 breech-block or plug is swung into position before the breech, inserted therein and locked, also with one continuous motion of the mechanism, and it has for its object to improve the construction and arrangement of such breech 20 mechanism, whereby the breech-block or plug can be more quickly, easily and certainly operated by means which are substantial in structure, positive in operation and mechanically simple of construction, and to these ends 25 my invention consists in the various features of construction and arrangement of parts adapted to operate in the manner hereinafter set forth.

Referring to the accompanying drawings: 30 Figure 1, is an end view of a gun, with the breech closed ready for firing. Fig. 2, is a plan view of the same. Fig. 3, is a vertical, longitudinal section of the same. Fig. 4, is an end view of the breech-block or plug. Fig. 35 5, is a detail view showing the racks attached to the plug. Fig. 6, is a plan of the same. Figs. 7 and 8 are, respectively, side and plan views of a wheel adapted to be used with the rack; and Fig. 9, is an enlarged detail. Fig. 40 10, is a partial side view showing the breech block withdrawn.

As before indicated, my invention relates more particularly to breech mechanism for ordnance, although, of course, it may be applied to guns of various sizes and styles, and while it is common to provide some sort of means for accomplishing the general purposes of my invention, and various mechanisms have been provided for doing this, it is the 45 object of my invention to improve on all these means known to me, and to provide mechanism which shall overcome some of the diffi-

culties inherent to the usual constructions. It is common to lock the breech-block or plug in the breech of the mechanism, by means of 5 interrupted screw-threads, and I have shown my invention as applied to a gun of such construction, in which, in order to remove the breech-block, it is first necessary to partially rotate the plug, and then withdraw it longitudinally from the breech. This has heretofore been accomplished in various ways and by various means, in some of which there has been a torsion strain upon the plug as it is withdrawn from the breech onto the tray for 65 supporting it, and one of the principal objects of my invention is to provide a mechanism which shall avoid this torsion strain, and thereby facilitate the movement of the plug, and the operation of the mechanism. 70

My invention further contemplates improvements in the means for starting the plug and overcoming its adhesion with the breech, especially in connection with guns in which a gas-check is used, and in which it requires a 75 greater amount of force to start the breech-block, and the greatest strain is exerted at that moment, and while this and other objects are accomplished by the mechanism which I am about to describe, it will be understood that my invention is not limited to the precise details of construction set forth, as these may be varied by those skilled in the art, without departing from the essential features of the invention, and parts of my invention may be used in combination with each other or with other equivalent devices. 80

In the breech A, of a gun, of any desirable construction, is an opening with interrupted threads for the reception of the plug, and 90 upon the removable breech-plug B, are correspondingly interrupted threads, whereby the breech-plug may be inserted and secured by a partial rotation, as usual. At the rear of the breech a tray C, is provided for the reception of the plug, which tray is suitably supported so that it may be swung to one side with the plug, after the latter is withdrawn from the breech onto the tray. As shown, the tray is supported by an arm s, extending from a sleeve t, pivoted to the bracket D, as for instance, through the medium of a vertical shaft E², passing through bearings in the bracket D, and rotated through the me- 95 100

dium of a worm wheel E' on the shaft, and a worm H upon a shaft H' turning in bearings on a bracket H² bolted to the breech; the said shaft H' being revolved by any suitable means. When revolved by hand, the shaft H' is provided with a crank arm H². Upon the tray C, are parallel ribs or rails c, c, adapted to longitudinal grooves b, b, in the plug, which grooves are in a position to coincide with the rails when the plug is turned to position to disengage its threads from those of the breech, ready for removal, and the said grooves b, b, are of such length that the ends of the grooves will abut against the ends of the rails when the plug is withdrawn to its full extent.

In order that the swinging tray C may be held fixedly in place to receive the plug, I provide it with a locking device of any suitable character, that will lock the tray in position against the breech, and in order that the plug may be expeditiously swung out of position opposite the breech when it is fully upon the tray, I provide means whereby when the plug reaches this position, the said locking device will be released. Different forms of locking devices arranged to effect these results may be employed. As shown, there is pivoted to the tray a lever of the first order C', having at one end a hook c', which when the tray is in position against the breech, engages a hook a' upon the breech and locks the tray to the breech, a spring c⁶ tending to hold the parts in this position, while the projecting end or handle c' of the lever permits the latter to be manipulated by hand. A lug c³, with the inner corner beveled, extends upward from near the outer end of the lever C' into position to be struck and depressed by the plug B, as it arrives at its outer position upon the tray, so that the lever C' is thereby tilted to disengage its locking end. Upon the lever C' is another lug c³, which normally is below the upper face of the tray, but which when the plug is fully out and the outer end of the lever C' is depressed, is brought opposite a shoulder, not shown, on the plug and holds the latter in position upon the tray, preventing it from sliding forward when the parts are swung back into place to insert the plug.

In order to lock the lever C', with its inner end in an elevated position to hold the plug with certainty in place, I make use of a second locking device of a suitable character. For instance, a cross-bolt c⁴, sliding in a slot x', extending transversely through the lever C', extends beyond one side of the lever in position to engage a shoulder c⁵ on a projection of the tray, when the inner end of the lever C' is elevated.

In order to automatically remove the bolt from the shoulder c⁵, when the tray is swung inward, I provide the bolt with a rod c¹⁰, extending forward and projecting beyond the end of the lever, so as to make contact with the breech of the gun when the tray reaches its inner position, thereby forcing back the

bolt and permitting the end of the lever to drop. A spring c¹², normally throws the bolt inward. Any other suitable lock for locking the lever C' may be substituted for that shown.

In order to remove the plug from the breech of the gun in the present construction, the plug has to be first turned or partially rotated in the breech to release the interlocking mutilated screw-threads and then withdrawn longitudinally from the breech and my invention is directed more particularly to the means whereby these operations are accomplished and I make use of what I term a compound operating wheel, which is arranged to engage suitable racks applied to or formed on the plug. The compound wheel is constructed so as to operate as a worm-wheel and as a spur gear or pinion, substantially as hereinafter described.

The plug is shown as provided with a segmental rack G, and with a longitudinal rack g², by means of which the rotary and longitudinal movements of the plug may be accomplished, and the compound operating wheel is arranged to co-operate with both of these racks. The wheel may be made so that it can be turned one or more revolutions to the extent necessary to turn the plug as far as desired, acting in this respect solely as a worm wheel, and after the plug is turned to the necessary extent, the wheel will present spur or pinion teeth or faces of a proper character and arrangement to engage the teeth of the rack g², and draw out the plug; or the wheel may be of such a size that a portion of the teeth engage the rack G to turn the plug, and another portion engage the rack g² to draw out the plug, depending upon the extent of rotation of the plug, and the pitch of the teeth of the wheel. To this end, the compound wheel E has practically two sets of teeth. That is, it has projections which may be of any suitable character and arrangement, with inclined faces v, that engage the inclined faces of the correspondingly inclined teeth v' of the rack G, and acting thereon as worm-threads to turn the plug in one direction or the other, and the projections on the wheel E have also vertical faces e which when the rack g² is brought into line with the wheel engage the vertical faces w of the teeth of the rack g², acting as spur or pinion teeth. As shown in Figs. 1 and 2, the worm faces of the wheel are formed by providing said wheel with inclined or broken spiral projections corresponding to sectional threads of a regular worm-wheel of proper character, the faces being of proper pitch to engage those of the teeth v' of the rack G, while the spur or pinion faces are formed by cutting vertically through the worm teeth, as shown, so that the upper and under sides of the projection on the periphery of the wheel E, have a proper pitch and angle to act as worm threads, and the vertical faces of the projections have the proper pitch and are properly spaced to constitute spur or pinion

teeth and engage the faces of the teeth of the rack g^2 . In order that the pinion faces may engage the teeth of the rack g^2 at the proper moment, I prefer to provide the rack G with 5 a lug or stop g' , so arranged as to make contact with the top face of the wheel E , at the moment that one of the vertical or pinion faces of the wheel E is brought against the first of the vertical faces w of the rack g^2 . 10 when the wheel E will then at once begin to act as a pinion to draw the rack and its plug longitudinally outward. If the periphery of the wheel E is greater than the length of the rack g^2 it is not necessary to sub-divide the 15 worm threads throughout the whole extent of the wheel.

While the construction and arrangement illustrated in Figs. 1 and 2 are effective to the end desired, the teeth of the compound 20 wheel E in some cases, would be too much weakened in securing the vertical or pinion faces by sub-dividing the worm threads at close intervals, and I, therefore, for this purpose, prefer the construction of wheel and 25 rack illustrated in Figs. 5, 6, 7 and 8, in which the worm thread sections f, f , over-lap each other, as shown, each having upper and lower faces of proper pitch, but each terminating in a vertical end face e , which acts as a spur 30 or pinion face, and the teeth of the rack g^2 are sub-divided instead of being continuous, each tooth having an inclined slot u across it, adapted to receive a portion of one of the 35 worm thread sections, so that the ends of said sections bear on the faces w of the said teeth, while the intermediate portions of the said sections will enter the slots u . By this means the teeth of the wheel E may be made of a size to secure all the strength necessary 40 for effective operation under all circumstances.

Greater strength may be imparted to the teeth of the rack g^2 by forming only side notches, instead of continuing the groove u 45 entirely across the tooth, leaving an intermediate web, as shown at u' , Fig. 8, each of the worm thread sections being cut away to form a vertical recess u' (dotted lines Fig. 7) to receive the web u' , and this will not materially 50 weaken the teeth of the wheel E .

It will be seen that the action in withdrawing the plug and also in inserting it, is a continuous action, resulting from the revolution 55 of the wheel E in each case continuously in one direction. Thus, when the plug is in place, the revolution of the wheel E will first cause the teeth of the wheel to act as worm threads to turn the rack G and the plug until the stop g' is in contact with the face of the 60 wheel, when the latter continuing its movement, will act as a spur or pinion upon the rack g^2 to draw out the plug, and when the latter is fully out, its contact with the lug c^2 will tilt the lever C' and unlock the tray from 65 the breech, and the tray will then swing around carrying the plug from opposite the breech, the lever C' being then locked in

place by the bolt c^4 . When the movement of the wheel E is reversed, the plug being locked upon the tray, cannot be moved thereon and therefore, the plug and tray will swing together until the tray is in contact with the breech, when the lock c^4 will be thrown back and the locking lever C' will engage the hook a' , releasing the plug, which can then slide 75 inward upon the ribs c, c , under the pinion action of the wheel E , until the plug is fully in place, when the continued revolution of the wheel E will cause it to again act as a worm and turn the plug until it is seated in 80 the breech.

It will be observed that while the plug is being withdrawn longitudinally, there is no torsional strain or tendency to rotate the plug and it slides freely upon the ribs of the tray. 85

In order to overcome the adhesion of the plug, which is apt to occur after firing, especially when a gas check is used as shown, and relieve the strain upon the teeth of the wheel E , I provide a projection or starting lug O , which 90 is arranged preferably upon the side of the wheel E in such a position as to engage an extension or projection P of the curved rack G at the moment the plug reaches the proper position for the spur or pinion teeth to engage the rack to withdraw it from the breech. Thus it will be seen, at this moment not only does the face of one or more of the teeth e impinge upon the face of the teeth w of the rack and exert a pressure tending to withdraw the 100 plug longitudinally, but the tooth O also impinges upon the face of the extension P and operates to aid in starting the plug and overcoming its adhesion, so that the strain is divided between the teeth e and the prolonged 105 tooth O . In this way I am enabled to exert the greater strain necessary in starting the plug, without danger of injuring the teeth of the wheel, as the additional tooth O furnishes a greater wearing surface and takes a part of 110 the strain at the moment of starting the plug.

I claim as my invention—

1. The combination with the breech and plug of a gun, of a curved rack and a straight rack upon the plug, and a compound operating wheel E provided with teeth having both worm faces engaging the curved rack and spur or pinion faces engaging the straight rack, substantially as set forth. 115

2. The combination with the breech and 120 plug of a gun, of a curved rack and a straight rack upon the plug, a compound wheel having teeth provided with worm faces adapted to the teeth of the curved rack, and spur or pinion faces adapted to the teeth of the straight 125 rack, and a projection or stop upon the plug arranged to make contact with the face of the wheel when the plug is turned to bring the straight rack in position to engage the teeth of the wheel substantially as set forth. 130

3. The combination with the breech and plug of a gun, of a swinging tray arranged to receive the plug, a curved rack and a straight rack upon the plug, and a compound

- wheel having teeth with faces adapted to engage the teeth of the curved rack, and other faces adapted to engage the teeth of the straight rack, substantially as set forth.
- 5 4. The combination with the removable plug of a gun, of a curved rack and a straight rack, and a compound operating wheel provided with worm teeth sections engaging said curved rack and arranged to over-lap each 10 other, the said sections having faces at the ends adapted to the faces of the teeth of the straight rack, substantially as set forth.
5. The combination with the breech and plug of a gun, of a curved rack and a straight 15 rack, and a plug-operating wheel having worm teeth sections over-lapping each other and with vertical end faces, the teeth of the straight rack having recesses adapted to receive portions of the said worm thread sections, substantially as set forth.
6. The combination with the breech and plug of a gun, of racks secured to the plug, a wheel having teeth engaging the racks, the wheel being provided with a starting lug arranged to engage a projection on the rack, substantially as described.
7. The combination with the breech and plug of a gun, of a curved and straight rack upon the plug, a compound wheel having worm and spur teeth to engage the respective racks and provided with a projection or prolonged tooth to engage a projection on the rack, substantially as set forth.

In testimony whereof I have signed my name to this specification in the presence of 35 two subscribing witnesses.

OWEN F. LEIBERT.
